UNITED STATES PATENT OFFICE.

ALPHONSE H. KURSHEEDT, OF NEW YORK, N. Y., ASSIGNOR TO KURSHEEDT MANUFACTURING COMPANY, OF NEW YORK.

DESIGN FOR TRIMMING.

SPECIFICATION forming part of Design No. 35,132, dated September 24, 1901.

Application filed August 24, 1901. Serial No. 73,210. Term of patent 7 years.

To all whom it may concern:

Be it known that I, ALPHONSE H. KURSHEEDT, a citizen of the United States, residing at New York, in the county and State of New York, have invented and produced a new, useful, and original Design for Trimmings, of which the following is a specification, reference being had to the accompanying drawings, forming part thereof.

In the drawings, Figure I is a plan or face view of a trimming embodying my design; and Fig. II is a sectional view thereof, showing the longitudinal ribs or tucks.

In the drawings, *a* is a trimming of a general strip form, having at the middle thereof a series of tucks, ribs, or corrugations *b*, ex-

tending longitudinally of the trimming, and having a rounded contour at the top sloping laterally of the trimming. The trimming is bordered by tucks, ribs, or corrugations *c*, of greater width than the ribs or corrugations *b* in the middle of the trimming and having rounded surfaces sloping laterally in the direction of the width of the trimming.

What I claim is—

The design for trimming substantially as herein shown and described. 25

A. H. KURSHEEDT.
